US00D788682S

(12) **United States Design Patent** (10) Patent No.: **US D788,682 S**
(45) Date of Patent: **** Jun. 6, 2017**

(54) **BOAT**

(71) Applicant: **Jin Yong Chun**, Gyeonggi-Do (KR)

(72) Inventor: **Jin Yong Chun**, Bucheon-si (KR)

(**) Term: **15 Years**

(21) Appl. No.: **35/500,840**

(22) Filed: **Oct. 22, 2015**

(80) **Hague Agreement Data**

Int. Filing Date: **Oct. 22, 2015**

Int. Reg. No.: **DM/089339**

Int. Reg. Date: **Oct. 22, 2015**

Int. Reg. Pub. Date: **Apr. 22, 2016**

(51) LOC (10) Cl. **12-06**

(52) U.S. Cl.

USPC **D12/300**

(58) **Field of Classification Search**

USPC D12/300, 302, 303, 304, 307, 310-314,
D12/316-317

CPC B63B 17/00; B63B 17/02; B63B 35/81;
B63B 35/816; B62B 21/04
